CLAIM

The ornamental design for a paint cover, as shown and described.

DESCRIPTION

FIG. 1 is a top front perspective view of a paint cover; FIG. 2 is a front elevation view thereof, the rear, right and left elevation views being mirror image thereof; FIG. 3 is a top plan view thereof;

FIG. 4 is a bottom plan view thereof;

FIG. 5 is a bottom front perspective view thereof; and, FIG. 6 is a detail section view thereof, along line 6-6 in FIG.

2.

The broken line showing of a sprinkler head in FIG. 5 is included for the purpose of illustrating and forms no part of the claimed design.
